UNITED STATES PATENT OFFICE

ANDREW D. RING, OF SCHENECTADY, NEW YORK, ASSIGNOR TO GENERAL ELECTRIC COMPANY, A CORPORATION OF NEW YORK

NEUTRALIZING DEVICE FOR VACUUM TUBES

Application filed June 5, 1929. Serial No. 368,704.

The present invention relates to the neutralization of feed back through the inter-electrode capacity of a vacuum tube or other electric discharge device, between circuits coupled by such device, and has for its object to provide an improved means for neutralizing the effects of such capacity to prevent feed back, which means is adapted to be applied directly to the tube or device of the electric discharge type without involving long external connections to the circuits coupled thereby.

The means of the present invention is particularly adapted for neutralizing the capacity coupling between the plate and grid circuits of a three element vacuum tube when such circuits employ relatively long leads between the tube and the remaining elements of said circuits.

The invention will be better understood from the following description when considered in connection with the accompanying drawing and its scope will be pointed out in the appended claims.

In the drawing, the figure is a circuit diagram of two circuits coupled by a three element vacuum tube, and provided with a neutralizing means embodying my invention.

Referring to the drawing, 5 is an electric discharge device of the vacuum tube, three element type, having a cathode 6, an anode 7, and a control electrode or grid 8. Between the control grid and the cathode is connected an excitation or input circuit 9 having suitable tuning elements such as an input transformer 11 and a tuning condenser 12 and relatively long circuit leads 13 between the tuning elements of the circuit and the tube. The input circuit includes a suitable bias battery or other source of bias potential 14 for the control grid.

Connected between the anode 7 and the cathode 6 is an output circuit 17 which is coupled to a tuned circuit 18 and includes a source of anode potential 19. This circuit

is also provided with relatively long leads 20 between the essential elements of the circuit and the tube. Tuning elements 11 and 12 represent any suitable input impedance while the coupled circuit 18 represents any suitable output impedance for the tube.

In an arrangement of this character employing relatively long connecting leads between the input and output impedances and the tube, it is difficult to provide a neutralizing means for preventing feed back of energy between the circuits coupled through the inter-electrode capacity of the tube. This is for the reason that with systems heretofore employed an additional connection lead is necessary between the tube and either the input or the output impedance for adjusting one or the other of these impedances to effect neutralization. In accordance with the invention the input and output impedances may be of any suitable type and located at any desired distance from the tube which serves to couple them, and the neutralizing means is applied directly to the tube substantially at its terminals.

The elements of the neutralizing means are a tapped inductive reactance or transformer 21 and a neutralizing condenser 22 in series therewith. In practice these elements are embodied in a single instrument or device indicated within the dotted lines, which device is adapted to be connected directly to the terminals of the tube. Connection between the tube and the neutralizing device is made between one end of the transformer winding 21 and the anode 7 through condenser 22. The opposite end of the transformer winding is connected to the control electrode 8. A tap 23 is connected with the cathode. This divides the winding and places a separate section in shunt with each input and output circuit.

To prevent a short circuit on the bias battery 14, a blocking condenser may be included in circuit with it and the transformer 21.

In the present example this condenser is placed in the control electrode connection as indicated at 15. It should be understood that this condenser is used only when necessary to block the circuit against direct current flow.

5 The neutralizing condenser 22 may be of any suitable type having a capacity substantially equal to the inter-electrode or anode-grid capacity of the tube although it is possible to vary this capacity if the transformation ratio in the transformer 21 is changed in accordance therewith. The transformer is 10 preferably one continuous inductive reactance winding but divided electrically as shown 15 into primary and secondary sections by the tap connection, and serves the purpose of reversing the phase of the voltage feed back through the neutralizing condenser to the grid of the tube. For this purpose the winding sections or transformer windings thus 20 established are closely coupled magnetically and in addition should possess relatively high reactance compared with the input or output 25 reactances of the tube. Any other suitable arrangement providing magnetically close coupled transformer windings in opposing phase relation may be provided however, although the continuous tapped winding of the present example is at present preferred.

30 In the present example, tap 23 is a mid-tap in the winding and is grounded or connected to the cathode circuit, thus providing a common connection for both windings established by the tap, with the cathode and 35 protecting the tube in case the neutralizing condenser 22 breaks down, under which condition the voltage of the anode circuit from source 19 may be applied to the grid of the tube depending upon the external circuit and 40 the position of blocking condenser 15 if used. The mid-tap connection with the cathode also serves as an additional means for stabilizing the voltage at a fixed point on the reactor 21 or between the transformer windings. In the 45 present example the cathode lead is grounded as indicated at 24.

The action of this circuit is such that neutralizing voltage supplied through the neutralizing condenser 22 is reversed due to the 50 transformer action and appears on the grid of the tube in reverse phase to that voltage which is fed directly through the tube capacity, with the result that neutralization is accomplished.

55 This neutralizing means is easily applied to the coupling tube and serves to neutralize the coupled circuits regardless of the length of the connections thereto, and since it may be applied directly to the tube at its terminals or substantially at its terminals, no additional circuit leads between the impedances and the tubes are involved. For attachment to the circuits of a tube, the device is provided with an anode terminal 25, a cathode terminal 26 and a control electrode terminal 27.

It has been found that in coupling circuits transmitting high audio frequencies, as for example through circuit 9 and leads 13, the neutralizing means of the present invention serves to prevent the loss of energy which is ordinarily by-passed to the filament due to the capacity action of the tube and serves to reinforce the input energy through the feed back action of the neutralizing circuit with the result that there is no high frequency loss because of tube capacity.

70 The neutralizing means of the present invention has been successfully applied to tuned high frequency input and output circuits coupled by a three element tube substantially as shown, when leads connecting the tuning elements of the circuits and the tube were several feet in length, thus clearly demonstrating its effectiveness under such unusual conditions in a high frequency circuit. Since the neutralizing means is applied directly to the tube, it serves to neutralize the effect of the distributed capacity of the long leads without introducing similar leads in the neutralizing circuit as would be 75 the case with known neutralizing systems.

80 What I claim as new and desire to secure by Letters Patent of the United States, is:

1. The combination with an electric discharge device having an anode, a cathode and a control electrode, of an input circuit connected between said control electrode and said cathode, an output circuit connected between said anode and said cathode a source of anode potential connected in said circuit, and a neutralizing device including an inductance connected at one end with the control electrode and at the other end with the anode, a neutralizing condenser interposed in circuit with said inductance and its connection with said anode, and a tap on said inductance connected with the cathode.

2. The combination with an electric discharge device having an anode, a cathode and a control electrode, of an input circuit connected between said control electrode and said cathode, an output circuit including a source of anode potential connected between said anode and said cathode, and a neutralizing device including a winding connected in shunt to the output circuit and said source of potential in series, a neutralizing condenser in circuit with said winding, and a second winding connected in shunt to the input circuit, said windings being electro-magnetically close coupled in opposing phase relation.

3. The combination with an electric discharge amplifier device having a control electrode, a cathode and an anode, of a device for neutralizing the inter-electrode capacity of the amplifier device in connection with input and output circuits having relatively long connecting leads with said electrodes, said means being adapted to be ap-

plied directly to the amplifier device and including an anode terminal, a control electrode terminal, and a cathode terminal for connection with the electrodes of said amplifier device, an inductance winding connected between said anode and control electrode terminals, a neutralizing condenser connected between said winding and the anode terminal, and a tap on said winding connected with said cathode terminal.

In witness whereof, I have hereunto set my hand this 4th day of June, 1929.

ANDREW D. RING.
